(57) **CLAIM**

The ornamental design for a hand truck, as shown and described.

DESCRIPTION

FIG. 1 is a front, top and right side perspective view of a hand truck, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is an enlarged view of portion 9 shown in FIG. 1; and, FIG. 10 is an enlarged view of portion 10 shown in FIG. 1. The dot-dash broken lines depict the boundaries of the enlargements, and form no part of the claimed design.

1 Claim, 10 Drawing Sheets
